Attorney

UNITED STATES PATENT OFFICE.

FRANK MEYERS, OF DUBUQUE, IOWA.

RADIATOR-FITTING.

1,259,427.

Specification of Letters Patent. Patented Mar. 12, 1918.

Application filed October 4, 1917. Serial No. 194,764.

To all whom it may concern:

Be it known that I, FRANK MEYERS, a citizen of the United States, residing at Dubuque, in the county of Dubuque and State 5 of Iowa, have invented certain new and useful Improvements in Radiator-Fittings, of which the following is a specification.

This invention relates to radiators and it is the principal object of the invention to 10 provide an improved return pipe fitting therefor, whereby steam or vapor will be positively prevented from passing from the radiator into the return pipe.

Another object of the invention is to provide 15 a novel form of fluid seal in the connection between the radiator outlet and the return pipe.

The foregoing together with additional 20 advantageous details and arrangement of parts of the preferred embodiment of my invention will be clear from the specific description hereinafter contained, when read in connection with the accompanying drawings forming part thereof, wherein said embodiment of the invention is illustrated for 25 the purpose of facilitating a full understanding of the present improvements.

In the drawings:—

Figure 1 is a vertical section through the 30 improved fitting and a fragment of a radiator loop; and

Fig. 2 is an end elevation of the improved fitting.

Having more particular reference to the 35 drawings and in connection with which like reference characters will refer to corresponding parts in the several views, 1 represents a fragment of a radiator loop having a screw threaded outlet opening 2 formed in 40 one side thereof, whereby connection between the usual form of return pipe may be effected.

Turned into engagement with the screw 45 threaded outlet opening 2 is an eccentric bushing 3, which bushing is adapted to have a short conduit 4 turned into engagement therewith, the outer marginal edges of which are beveled as at 5 and elbow 6 also provided with beveled edges is engaged with 50 the beveled edges 5 of the short conduit 4 and is connected thereto through the me-

dium of a union nut 7; it of course being understood that the said elbow 6 is connected to the usual return pipe included in the heat distributing system. That end of the 55 short conduit 4 which is turned into engagement with the eccentric bushing 3 is partially closed by an end piece 8 formed integral therewith and having a screw threaded opening and a slot 9 extending therethrough whereby a vent will be provided.

Passing through the elbow 6, the short conduit 4 and the screw threaded opening formed in the end piece 8 is a conduit 9 having the opposite ends thereof curved as 60 at 10, which curved ends are arranged in the elbow 6 and the radiator loop, it being noted that the curved end 10 arranged in the said radiator loop is arranged below the water line therein. To prevent undue movement of the tube 9, the intermediate portion of the same is screw threaded and turned into engagement with the screw threaded opening formed in the said piece 8.

From the foregoing, it will be readily understood by those skilled in the art that with my improved connection the escape of steam or vapor from a radiator provided with the same is positively prevented, since, the tube 9 with its curved ends 10 is so arranged as to prevent the passage of the steam or vapor thereinto. Thus, the efficiency of the radiator is materially increased.

The connection by reason of its exceedingly simple construction may be arranged 85 upon the conventional type of radiators without material alteration thereto and in but a minimum amount of time.

Manifestly, the construction shown is capable of considerable modification and 90 such modification as is within the scope of my claims, I consider within the spirit of my invention.

I claim:—

1. In combination with a radiator and the 95 return pipe therefor, a short conduit turned into engagement with the radiator outlet opening and having one end partially closed, the remaining end of the short conduit being connected to the return pipe and 100 a tube having its opposite ends curved passing through said short conduit into en-

gagement with the radiator and the return pipe.

2. In combination with a radiator and the return pipe therefor, a conduit engaged with the radiator outlet having one end partially closed, the remaining end of said conduit being connected to the return pipe, and a tube having its opposite ends curved down-

wardly passing through said conduit into engagement with the radiator and the return pipe, one end of the tube being arranged below the water line in the radiator.

In testimony whereof, I affix my signature hereto.

FRANK MEYERS.
